No 283

Washburn Race of Seneca Falls N.Y.
Letters Patent. No 283. Dated May 14. 1850.

The Schedule referred to in these Letters Patent and making part of the same.

To all whom it may concern:

Be it known that J. Washburn Race of Seneca Falls, in the County of Seneca and State of New York, have invented or produced a new and ornamental set of castings for a stove; and I do hereby declare the following to be a full and exact description thereof, reference being had to the accompanying drawings making a part of this specification. Fig. 1. is a side elevation of a stove composed of a sheet iron tube combined with my ornamentally designed castings: Fig. 2. a vertical longitudinal section of the top plate A. of the stove: Fig. 3. a longitudinal vertical section of the bottom plate B. of the stove: Fig. 4. an enlarged view of the stove door C. and its frame D. detached from the stove; and Fig. 5. a transverse section through the stove door and its frame.

Fig. 6. is a top view of a broken section of the top plate A. of the stove full size, and Fig. 7. a vertical section through the same: Fig. 8. is a top view of a broken section of the bottom plate B. of the stove, and Fig. 9. a section through the same.

Similar letters indicate like parts in all the figures.

E. is a vase placed upon the centre of the top plate A. which is of an ornamental shape, and has its surface covered with raised figures representing roses &c, and supplied with fancifully devised handles, as represented in Fig. 1. The outlines of the top and bottom plates A. B. are of an oval form, and the form of their vertical sections is shown by Figs 2 and 3.

The upper plate A. is ornamented by raised figures representing foliage, and by a series of openings within a portion of the said figures, as shown by the drawings in Figs 1 and 6.

The lower plate B. is ornamented by raised configurations representing foliage, as shown in Figs 1 and 8.

The door C. and its frame D. is ornamented with raised

Des. 283

fancy configurations as shown in Fig. 4.

What I claim as my invention and desire to secure by Letters Patent, is the ornamental shape and configuration of the respective pieces of casting for a stove as represented in the accompanying drawings & herein specified.

The above Specification signed and witnessed this twenty seventh day of March 1850.

Witnesses.
